T. G. MARTIN,
SUBSTATION TELEPHONE CIRCUITS,
APPLICATION FILED JAN. 21, 1921.

Patented Aug. 1, 1922.

—Inventor—
Talbot G. Martin
Chas. H. Caudle
R. R. 1.

UNITED STATES PATENT OFFICE.

TALBOT G. MARTIN, OF CHICAGO, ILLINOIS, ASSIGNOR TO AUTOMATIC ELECTRIC COMPANY, OF CHICAGO, ILLINOIS, A CORPORATION OF ILLINOIS.

SUBSTATION TELEPHONE CIRCUITS.

1,424,368.

Specification of Letters Patent. Patented Aug. 1, 1922.

Application filed January 21, 1921. Serial No. 438,987.

To all whom it may concern:

Be it known that I, TALBOT G. MARTIN, a citizen of the United States of America, and a resident of Chicago, Cook County, and State of Illinois, have invented certain new and useful Improvements in Substation Telephone Circuits, of which the following is a specification.

The present invention relates in general to substation telephone circuits, but more particularly to substation circuits for use in automatic telephone systems; and the object of the invention, broadly stated, is to provide a novel and effective circuit arrangement for introducing a well known type of calling device, or impulse sender, in a standard Bell common battery telephone circuit.

Calling devices have been associated with telephone circuits of this type before, and it has been the object of prior inventors along this line, to provide means for preventing clicks, or objectionable noises, in the telephone receiver when the impulse sender is being operated. It has also been considered necessary to shunt out the transmitter during the transmission of impulses, as the uncertain resistance of this member is apt to have a bad effect on the impulses.

To these ends it has been the practice to provide contact springs for the impulse sender, which when the sender is moved from normal are effective to open the receiver circuit and to shunt the transmitter. The main objects sought are thus accomplished, but the circuit arrangements used heretofore do not attain the desired results as efficiently as possible. The principal trouble is in connection with the ringer circuit. It is desirable to bridge the ringer across the line without intervening switch hook contacts, as contacts for this purpose are not provided on the standard telephones, and it has been the practice heretofore to connect the ringer directly across the two line wires. This is not altogether satisfactory, for the ringer is liable to tap the gongs during the transmission of impulses, and in addition the bridged ringer

and condenser are liable to injuriously affect the quality of the transmitted impulses. It is the object of the present invention, considered more specifically, to remove the defects pointed out, and the invention consists in an improvement or revision of the cir-

cuit arrangements whereby existing advantages are retained, while the further advantage of entirely eliminating the objectionable ringer circuit difficulties is secured in a simple and effective manner.

The improved circuits will now be described with reference to the accompanying drawings, in which Fig. 1 is a wiring diagram of the invention as applied to a wall telephone, while Fig. 2 is a simplified circuit diagram.

Referring first to Fig. 2; the talking circuit, as before stated, is of the well known Bell common battery type. With the receiver removed from the hook, the transmitter T and the winding 4 of the induction coil I are bridged across the two line wires 2 and 3, while the receiver R in series with the winding 5 of the induction coil and the condenser C is connected in shunt of the transmitter. The transmitter and receiver circuits, as pointed out above, are of course normally open at the usual switch hook contacts, and are closed by the raising of the switch hook when the receiver is removed.

Associated with the lower side of the line is a subscriber's impulse sender, which is indicated by the reference character S. This sender, or calling device, may be of the type which is shown and described on pages 34 and 35 of Automatic Telephony by Smith and Campbell, published by the McGraw-Hill Book Company. It comprises essentially a pair of impulse springs 6 and 7 which are controlled by a cam (not shown) through the medium of a finger hold dial (also not shown), and three shunt springs 8, 9, and 10, together with suitable means for shifting spring 9 away from spring 10 and into engagement with spring 8 whenever the calling dial is turned from its normal position. The impulse springs 6 and 7 are connected in series with the lower line wire 3 and their function is to produce momentary interruptions of the line circuit for the purpose of operating the central office switches. The function of the set of springs 8, 9 and 10 is to provide for opening the receiver circuit and for shunting the transmitter when the calling device dial is being operated. In order to accomplish this object it will be seen that the receiver circuit is taken through normally closed contact springs 10 and 9, so that when these springs are separated by the operation of 110

the calling dial the receiver circuit will be broken. It will be seen further that the shunt spring 8 is so connected that when it is engaged by the spring 9 under the above mentioned circumstances, the transmitter T will be directly short circuited. This provides an impulsing circuit which includes only the impulse springs 6 and 8 and the primary winding 4 of the induction coil, and since the receiver circuit is broken while impulses are being transmitted over this circuit, the subscriber will not be annoyed by clicks or noises in his receiver.

Attention is now directed to the manner in which the ringer M is connected. One side of the ringer is connected to the upper line wire 2, while the other side of the ringer is connected to the condenser C, the other side of which is in turn connected to the lower side of the line at a point between the impulse spring 7 and the transmitter T. It will be seen then that since the impulse springs 6 and 7 are normally closed, the ringer and condenser C are for all practical purposes bridged directly across the line wires, at least this is true so far as the reception of incoming ringing currents is concerned, which are intended to operate the ringer and notify the subscriber that he is being called. But when the telephone is being used for an outgoing call and the impulse sender is being operated, the impulse springs 6 and 7 not only interrupt the usual direct current bridge across the line but they also interrupt the circuit of the bridged ringer. It follows that the line conductor 3 is entirely disconnected from the other line conductor every time the impulse springs are separated, and there is nothing bridged across the line at the substation which can in any way affect the quality of the impulses. Furthermore, since the ringer circuit is also interrupted by the impulse springs, the condenser C is not charged and discharged by the opening and closing of the impulse springs as would be the case if it was connected directly across the line conductors 2 and 3, and the ringer is thus prevented from tapping the gongs.

In Fig. 1 a specific form of the circuit shown in Fig. 2 has been drawn out in detail. The apparatus at the right comprising the transmitter T and the calling device S is intended to be mounted on the door of the telephone box; while the apparatus at the left, comprising the receiver R, switchhook H, ringer M, induction coil I, and condenser C are mounted in the customary manner within the box itself. It will be seen that there are five conductors connecting the apparatus which is mounted on the door with the other apparatus, and these conductors are preferably formed into a flexible cable in order to permit the opening and closing of the door. If desired, however, the door may be provided with a plurality of hinges,

through which the required connections are made. Suitable binding posts are provided in the base of the telephone box for connecting the line wires and the receiver cord, and these binding posts are, of course, connected with the appropriate parts of the apparatus. A series of binding posts are also preferably provided on the inside of the door in order to facilitate the connection of the wires coming from the transmitter and from the calling device.

The operation of the telephone substation embodying the new circuit is as follows: Referring to Fig. 2, when the receiver is removed to initiate a call, the switch hook lever H is permitted to rise and the previously described circuits of the transmitter and receiver are closed. Responsive to the closure of the transmitter circuit current is supplied to the transmitter from a bridged battery at the central office (not shown) over the following path: line conductor 2, winding 4 of the induction coil I, right hand switchhook contact, transmitter T, and impulse springs 7 and 6 to line conductor 3. The bridge at the central office which includes the battery, may also, in accordance with the usual practice, include the controlling relay of an automatic switch, the circuit of such relay including, therefore, the transmitter bridge at the substation. It follows that the calling subscriber, by suitably manipulating his calling device dial, may produce a series of interruptions in the circuit of the controlling relay to bring about the operation of said switch.

It should be noted in this connection that when the dial is turned from its normal position, the substation loop is completed over a path which extends from the line conductor 2 by way of the winding 4 of the induction coil I, both contacts of the switchhook H, spring 9, spring 8 and the impulse springs 7 and 6 to the line wire 3. It will thus be seen that the variable resistance of the transmitter is excluded from the impulsing circuit. Succeeding operations of the dial will now result in the operation of additional automatic switches at the exchange, until the connection is finally completed to the line of the called subscriber, it being understood that all the switches are provided with controlling relay bridges which, with the exception of the bridge in the last switch, are successively cut off from the line after their associated switches are operated.

The connection having been completed, conversation may be held as desired. Since the operation of the automatic circuits is well known it is not thought to be necessary to devote any space to the description of such operation herein. When the receiver is replaced at the end of the conversation the transmitter and receiver circuits are broken at the switch hook contacts and further flow of direct current through the sub-

station from the exchange is prevented. As a result all the switches at the central office are released and restored to normal in the usual and well known manner. The substation is now in condition to receive incoming signalling currents which may come in over the line conductors 2 and 3 and traverse the ringer M and the condenser C, whereby the ringer is actuated to advise the subscriber 10 of an incoming call.

Having described my invention, what I consider to be new and desire to have protected by Letters Patent will be pointed out in the appended claims.

15. What I claim is:

1. In a substation circuit arrangement for telephone exchange systems, a receiver, a transmitter, normally open circuits for said transmitter and said receiver, a switch for 20 closing said circuits, an impulse sending device having a definite normal position, means for moving said device out of its normal position, means for returning said device to its normal position, contacts operated during the last mentioned movement of said device for sending impulses, a contact operated during said movements of said device for opening the circuit of said receiver, another contact operated during said 25 movements of said device for shunting said transmitter, a ringer, a condenser, and a cir-

cuit for said ringer including said condenser and the said impulse sending contacts.

2. In a substation circuit arrangement for telephone exchange systems, a receiver, a 35 transmitter, normally open circuits for said receiver and transmitter, means for closing said circuits, an impulse sending device, a pair of contact springs actuated by said device for transmitting impulses, means actuated during the operation of said sending device for opening the receiver circuit and shunting the transmitter circuit, a ringer, a condenser, and a circuit for said ringer including said condenser and the said pair of 40 45 contact springs.

3. In a telephone substation circuit, a receiver, a circuit therefor, a transmitter, a shunt circuit therefor, an impulse sending device, contacts controlled by said device 50 for transmitting impulses to the exchange, contacts controlled by said device for opening said receiver circuit and closing said shunt circuit whenever said device is moved from normal, a ringer and a circuit there- 55 for including said first named contacts, and a condenser included in the ringer circuit and also in the receiver circuit.

Signed by me at Chicago, Cook County, Illinois, this 17th day of Jan. 1921.

TALBOT G. MARTIN.
